FUEL BURNER CONTROL SYSTEM

John M. Wilson, Minneapolis, Minn., assignor to
 Minneapolis-Honeywell Regulator Company,
 Minneapolis, Minn., a corporation of Delaware

Application December 9, 1940, Serial No. 369,241

5 Claims. (Cl. 158—28)

This invention relates generally to automatic control systems for fuel burners, and more particularly to that type of system having a timed automatic safety switch for shutting the system down in the event that combustion is not established within a predetermined time following a demand for heat as evidenced by the closing of a main switch to the system.

In prior art systems wherein two or more electromagnetic relays are utilized in order to get the proper sequencing and safety functions, the safety switch actuator (usually an electric heater) is connected directly in series with one of the relays. This is customarily the first relay to be energized upon a demand for heat. In view of the fact that the current flow through the heater is limited by the reactance of the relay coil, the resistance of the heater must be fairly high in order to develop sufficient heat to give the safety switch the proper timing. A high resistance in the safety switch heater limits the pull-in voltage available for the relay, thus making it difficult in many instances to obtain the proper relation between the resistance of the heater and the number of turns in the relay coil.

It is an object of the present invention to obviate the above difficulty by energizing the relays substantially simultaneously and directing the current from both of them through the safety switch heater. This will materially increase the current flow through the heater with the result that the resistance of the heater may be reduced to substantially a quarter of the value required if only one relay is connected in circuit with it. Obviously, this will materially reduce the voltage drop across the heater and a much higher pull-in voltage for the relays is available.

A further object is to provide a system of the above type in which one relay controls an ignition device and the other relay controls the fuel feeding device, the arrangement being such that both relays are energized substantially simultaneously and the first relay is dropped out upon the establishment of combustion to deenergize the ignition device while the second relay is held in through a closed hot combustion switch.

Other objects reside in the various details of the circuit arrangement which are described in the following specification, reference being had to the single figure of the drawing which illustrates, schematically, an oil burner control system embodying my invention.

In the following description the control system will be referred to as controlling an oil burner although it will be appreciated that it is equally

applicable to the control of other types of burners, such as gas, powdered coal, etc.

Referring to the drawing the reference numeral 10 indicates a room thermostat in the form of a bimetal coil being fixed at one end and carrying at its free end a pair of resilient contact blades 11 and 12. These blades are so related to the stationary contacts 13 and 14 that on cooling of the bimetal 10 the blade 11 will first engage contact 13 and shortly thereafter the blade 12 will engage the contact 14. An electrical resistance element 15 is positioned to affect the temperature of the bimetal 10 in a manner to be described later.

Indicated generally at 20 is a cold contact assembly and 21 indicates a hot contact assembly. The cold contact assembly comprises three contact blades 22, 23, and 24 which are normally biased to open circuit position that is, when they are not acted on by any external forces the blades 23 and 24 will move to the left as a result of a biasing force so that the blades 24 and 23, as well as 23 and 22, will be out of contact with each other. The hot contact assembly comprises two contact blades 25 and 26 which are also normally in open circuit position as shown in the drawing.

These contact assemblies are adapted to be operated by means of a combustion responsive element which may be of any desired form but which is preferably in the form of a W-shaped bimetallic element 28, which is positioned to respond to the temperature of combustion and is usually placed in the stack. This element forms no part of the present invention but is preferably in the form shown in the patent to Willis H. Gille No. 2,196,671. One end of the element 28 is connected to a fixed part as shown at 29 and the other end is adapted to move in a straight line and actuate the rod 30. Two slip friction elements 31 and 32 are mounted on the rod 30, the element 31 actuating the hot switch 25, 26 and the element 32 actuating the cold switches 22, 23 and 24. The elements 31 and 32 have been illustrated more or less diagrammatically but preferably take the form of clutch type slip friction elements as shown in my co-pending application, Serial No. 260,071.

As the element 28 expands on an increase in temperature, it moves the rod 30 to the left as shown in the drawing and the slip friction element 31 first engages the blade 25 and moves it into electrical contact with the blade 26. Further movement of the rod 30 to the left will not have any effect upon the element 31 which will merely

slide with respect thereto. The movement of the rod 30 also carries the slip friction element 32 which in the position shown in the drawing is holding the cold switches 22, 23 and 24 in closed circuit position. As the rod 30 moves to the left, it first permits blade 23 to separate from blade 22 and thereafter permits the blade 24 to separate from blade 23, after which the element engages the stop 35. Further movement of the rod 30 is permitted by the slip friction between the element 32 and the rod. On a decrease in temperature the rod 30 is moved to the right carrying with it the two elements 31 and 32. The element 31 first permits the blade 25 to separate from blade 26 and the element 32 forces the blade 24 into contact with the blade 23 and then carries this blade into engagement with the blade 22. After blades 25 and 26 have separated, the element 31 engages the stop 36 after which the rod 30 slips with respect to this element.

It will therefore be seen that due to the slip friction connection between the rod 30 and the elements 31 and 32 that the hot and cold switches are actuated by a reverse in temperature changes and are not dependent upon the establishment of any definite temperature value. The switches are so arranged that on heating, the hot switch 25, 26 will always be closed prior to the opening of the switch 23, 24 and on closing the hot switch 25, 26 will open prior to the closing of the switch 23, 24. In other words, these switches overlap on heating but not on cooling.

This control system is provided with two electro-magnetic relays indicated at 40 and 41. The relay 40 when energized moves the switch blades 42, 43, 44 and 45 to closed position, and the relay 41 when energized moves switch blades 46, 47, 48 and 49 to closed position.

The reference numeral 50 indicates generally the usual type of safety switch which is biased to open circuit position but which is latch-closed by means of a thermal element which is the element 51. As shown, the thermal switch comprises a switch blade 52. The reference numeral 53 indicates the safety switch heater which is adapted to heat the thermal blade 51, and after a predetermined period of time to cause it to warp sufficiently to release the safety switch for movement to open position.

The ignition device is indicated diagrammatically at 55. This device may take the form of a spark transformer, or a hot wire igniter or any equivalent means for igniting fuel. The reference numeral 56 indicates an electrical device for controlling the feed of fuel and may be an electrically operated valve, or may take the form of the usual oil burner motor or any equivalent device.

Electrical energy is supplied to the system by means of the line wires 60 and 61 across which the primary winding 62 of the step-down transformer is connected. The room thermostat and relays are in the low voltage circuit which is supplied with power from the secondary winding 64 of the transformer 63.

Operation

The system is shown in the drawing with the parts occupying the position which they will occupy when the room thermostat 10 is satisfied and has been satisfied for a sufficient length of time to permit the hot combustion switch to open and both of the cold combustion switches to close. Under these conditions both of the relays will be deenergized as the circuit to the secondary

64 is opened at contact 13. The burner motor 56 and ignition device 55 will therefore be de-energized and the entire system will be at rest. Under these conditions the temperature in the room will begin to drop and the bimetallic thermostat 10 will first cause the switch blade 11 to engage the stationary contact 13. This will have no effect upon the system at this time due to the fact that the switch blade 48 and the contact blade 12 are both in open circuit position. On a further decrease in room temperature the thermostat 10 will move the switch blade 12 into engagement with the stationary contact 14. This will result in the energization of relay 40 through the following circuit: from one side of the secondary winding 64 through conductor 70, contact 13, switch blades 11 and 12, contact 14, conductors 71 and 72, safety switch heater 53, conductors 73 and 74, cold combustion switches 22, 23 and 24, conductor 75, relay winding 40, conductors 69 and 76, safety switch 52 and conductor 77 back to the other side of the secondary 64. It will be noted that the energization of this relay is impossible unless both of the cold combustion switches are closed. It is the operation of these switches therefore that times the recycle in this system.

The energization of the relay 40 results in switch blades 42, 43, 44 and 45 moving to closed circuit position. When the switch blade 45 moves to closed circuit position, it establishes the following circuit to the ignition device: from line wire 60 through conductors 78 and 79, switch blade 45, conductor 80, ignition device 55 and conductors 81 and 82 back to the other line wire 61. The closure of the switch blades 42 and 43 results in the establishment of a parallel circuit through the relay 40 shunting the cold switch 22, 23. This circuit may be traced from conductor 73 through conductor 83, switch blades 42 and 43 and conductor 84 to cold switch 23, 24 and hence through the relay 40. This circuit is set up so that the opening or chattering of the last to close cold switch 22, 23 will not drop out the relay 40. Closure of switch blade 44 results in the energization of relay 41 through the following circuit: from one side of the secondary winding 64, through conductor 70, contact 13, switch blades 11 and 12, contact 14, conductor 72, safety switch heater 53, conductors 73 and 83, switch blades 42 and 44, conductors 85 and 86, relay winding 41, conductors 88 and 76, safety switch 52 and conductor 77 back to the other side of the secondary winding 64. It will thus be seen that the safety switch heater 53 is connected in series with both of the relay windings 40 and 41 and that these two windings are connected in parallel with each other.

Energization of the relay winding 41 results in the closure of switch blades 46, 47, 48 and 49. The closure of the switch blade 49 establishes the following circuit through burner motor 56: from one line wire 60 through conductors 78 and 90, switch blade 49, conductor 91, burner motor 56 and conductors 92 and 82 back to the other line wire 61. Inasmuch as both the burner motor and ignition device have now been energized combustion should be established.

The closure of switch blades 47 and 48 result in closure of a parallel circuit through the relay winding 41 independent of the room thermostat switch 12, 14. This circuit may be traced from one side of the secondary winding 64 through conductor 70, contact 13, switch blade 11, bi-

metallic element 10, conductor 93, electric heater 15, conductor 94, switch blades 48 and 47, conductors 95 and 72, safety switch heater 53, conductors 73 and 83, switch blades 42 and 44, conductors 85 and 86, relay winding 41 and thus back to the other side of the secondary 64 through the safety switch 52. It will be noted that this parallel circuit for the relay winding 41 also passes through the safety switch heater 53 so that this heater still carries the current for both of the relay windings. The purpose of this circuit is to shunt the thermostat switch 12, 14 so that if this switch should open slightly due to vibration or other circumstances the relays 40 and 41 will not be dropped out. After the thermostat switch 12 and 14 is definitely moved to open circuit position due to an increase in room temperature, the electric heater 15 is brought into the circuit and heats the thermostat 10 in order to raise its temperature slightly above the room temperature in a manner to anticipate the rise in room temperature due to the energization of the burner. The burner will therefore be deenergized prematurely for the purpose of preventing over-shooting of the room temperature.

After combustion has been established the hot combustion switch 25, 26 will be moved to closed position by the slip friction element 31 in the manner already described. This will establish parallel circuits to the relay windings 40 and 41 independently of the safety switch heater 53. In other words this heater will be shunted and therefore effectively deenergized. These circuits may be traced from the room thermostat 10 to the switch blade 46 through either conductors 94 or 95, thence, through conductor 96 to the switch blades 25 and 26. From there the current to the relay winding 40 branches and goes through conductor 85, switch blades 44 and 43, conductor 84, cold switch 23, 24 and conductor 75, and the circuit for the relay winding 41 goes directly through the conductor 86. Therefore as soon as combustion has been established, as indicated by the closure of the hot combustion switch, the safety switch heater is immediately shunted out of the circuit. On further increase in combustion temperature the cold switch 22, 23 will open if it has not already done so. This will have no effect upon the system in view of the fact that a holding circuit for the relay winding 40 has already been established through cold switch 23, 24. A further increase in combustion temperature will result in the cold switch 23, 24 moving to open circuit position. As this switch is directly in series with the relay winding 40, it will deenergize this relay and the switch blades 42, 43, 44 and 45 will move to open circuit position. The opening of the switch 45 will result in the deenergization of the ignition device 55. The opening of the switches 42, 43 and 44 will have no effect upon the system in view of the fact that the relay winding 41 is now held in by a circuit extending through the switch blades 48 and 46 and the hot combustion switch 25, 26. This is the running condition of the system.

It will be noted at this point that inasmuch as the relay 41 is held in through the room thermostat switch 11, 13 and the hot combustion switch 25, 26 that either a flame failure or a movement of the thermostat 10 to satisfied condition will deenergize the relay 41. After such deenergization the system cannot restart until both of the cold switches 22, 23 and 23, 24 have been moved to closed position and until both of

the room thermostat switches 11, 13 and 12, 14 have moved to closed position. The closure of the cold switches 22, 23 and 24 is relied upon to provide the proper scavenger period following a flame failure or a power failure. It will be realized that the relay 41 will also drop out on a power failure and cannot be pulled in again until the combustion switches are in closed position.

If during the starting cycle ignition is not obtained the hot combustion switch 25, 26 will remain open and hence the safety switch heater 53 will remain energized. After a predetermined period of time (usually about ninety seconds) the heater 53 will have heated the thermal element 51 sufficiently for it to trip and release the safety switch 52 for movement to open circuit position. This switch must be manually reset before the system can again attempt to start.

It will be seen therefore that this system has been designed to provide all of the usual features of safety and that the main object of the invention has been attained by passing the current of both relay windings through the safety switch heater so that the resistance value of this heater may be materially reduced to increase the pull-in voltage of the relays.

Various changes and modifications of this invention may occur to those who are skilled in the art, and I therefore wish it to be understood that I intend to be limited only by the scope of the appended claims and not by the specific embodiment of the invention which I have disclosed herein.

I claim as my invention:

1. A fuel burner control system comprising in combination, an electrical fuel feeding device, first and second relays, a normally closed safety switch in control of said relays, an actuator which when energized for a predetermined period of time causes said safety switch to open, a circuit for said first relay including a main switch and said safety switch actuator, a circuit for said second relay including said main switch, said safety switch actuator and a switch which is closed when said first relay is energized, means actuated by said second relay upon energization for rendering said electrical fuel feeding device operative to deliver fuel to a point of combustion, means establishing a shunt circuit around said first relay switch whereby said second relay will remain energized independently of said first relay, and means opening the circuit to the first relay and safety switch actuator in response to the establishment of combustion.

2. A fuel burner control system comprising in combination, an electrical fuel control device, means for igniting the fuel, first and second relays, a normally closed safety switch in control of said relays, an actuator which when energized for a predetermined period of time causes said safety switch to open, a circuit for said first relay including a main switch and said safety switch actuator, a circuit for said second relay including said main switch, safety switch actuator, and a switch which is closed when said first relay is energized, a switch closed upon energization of said first relay for energizing said ignition means, a switch closed upon energization of said second relay for energizing said fuel control device, means operating in response to combustion for establishing a parallel circuit to said second relay independent of said first relay switch and the actuator for said safety switch, and means for subsequently opening the circuit to said first relay and actuator for the safety

switch and consequently deenergizing the ignition means.

3. A fuel burner control system comprising in combination, an electrical fuel control device, means for igniting the fuel, first and second relays, a normally closed safety switch in control of said relays, an actuator which when energized for a predetermined period of time causes said safety switch to open, a circuit for said first relay including a main switch and said safety switch actuator, a circuit for said second relay including said main switch, safety switch actuator, and a switch which is closed when said first relay is energized, a switch closed upon energization of said first relay for energizing said ignition means, a switch closed upon energization of said second relay for energizing said fuel control device, means operating in response to combustion for establishing a parallel circuit to said second relay independent of said first relay switch and the actuator for said safety switch, and means also operating in response to combustion for subsequently opening the circuit to said first relay and actuator for the safety switch and consequently deenergizing the ignition means.

4. A fuel burner control system comprising in combination, an electrical fuel feed control device, means for igniting the fuel fed by said device, first and second relays, a normally closed safety switch controlling the flow of electrical energy to said relays, an actuator which when energized for a predetermined period of time causes said safety switch to open, a circuit for said first relay including a main switch, said safety switch actuator, and a closed cold combustion responsive switch, a circuit for said second relay including said main switch, safety switch actuator, and a switch which is closed when said first relay is energized, a switch closed upon energization of said first relay for energizing said ignition means.

5. A fuel burner control system comprising in combination, an electrical fuel control device, means for igniting the fuel fed by said device, first and second relays, a normally closed safety switch controlling the flow of electrical energy to said relays, an actuator which when energized for a predetermined period of time causes said safety switch to open, a circuit for said first relay including a main switch, said safety switch actuator, and a switch which is closed when said first relay is energized, a switch closed upon energization of said second relay for energizing said fuel control device, means operating in response to combustion for establishing a parallel circuit to said second relay independent of said first relay switch and the actuator for said safety switch, and means also operating in response to combustion for subsequently opening the circuit to said first relay and actuator for the safety switch and said first relay and hence said ignition means.

6. A fuel burner control system comprising in combination, an electrical fuel feed control device, means for igniting the fuel fed by said device, first and second relays, a normally closed safety switch controlling the flow of electrical energy to said relays, an actuator which when energized for a predetermined period of time causes said safety switch to open, a circuit for said first relay including a main switch, said safety switch actuator, and first and second switches which are closed sequentially in response to a decrease in combustion temperature, a holding circuit closed by said first relay through the last to close combustion switch but independent of said first to close combustion switch, a circuit for said second relay including said main switch, safety switch actuator, and a switch which is closed when said first relay is energized, a switch closed upon energization of said first relay for energizing said ignition means, a switch closed upon energization of said second relay for energizing said fuel control device, means operating in response to combustion for establishing a parallel circuit to said second relay independent of said first relay switch and the actuator for said safety switch, said last to close combustion switch subsequently opening to deenergize said safety switch actuator, first relay, and ignition means.

JOHN M. WILSON.
